HUB CAP

John J. Palotsee, 330 E. Front St., Youngstown, Ohio

Filed Mar. 2, 1960, Ser. No. 59,600

Term of patent 14 years

(Cl. D14—30)

I claim:

The ornamental design for a hub cap, as shown.
